DUAL ORIFICE FEEDER

Frank L. O. Wadsworth, Pittsburgh, Pa., assignor to Ball Brothers Company, Muncie, Ind., a corporation of Indiana

Original application October 24, 1934, Serial No. 749,731. Divided and this application June 24, 1935, Serial No. 28,098

28 Claims.

(Cl. 49—55)

My invention relates to a new type of twin or dual orifice feeder which is designed and adapted to a speed of operation much greater than that of the existing forms of individual feeder apparatus and which is commensurate with that of the largest multiple arm feeding machines, and is a division of my copending application Serial No. 749,731, filed October 24, 1934.

The primary object of my invention is, therefore, to very materially increase the output of the maximum number of feeding machines which may be used in conjunction with the usual form of melting furnace and in conjunction with this purpose to also substantially reduce the floor space required for each such machine so that a larger number of forming units may be assembled in the space available for their installation. The combined results in increasing the number of feeders and forming machines is to very greatly augment the possible production of fabricated ware from a tank of any given size which usually has a melting capacity substantially in excess of that of the forming machine equipment which can be installed in front of it.

Another object of this invention is to provide means for establishing two continuously flowing streams of molten glass through dual or twin orifices in a forehearth structure, each of which is composed of a series of regularly recurrent sections of enlarged diameters connected together by sections of reduced diameters that are adapted to be severed, at these points of reduced diameters, into individual mold charges.

A further object is to provide novel means for alternately severing each of said streams, at the points of reduced diameters, into individual mold charges.

A still further object is to provide a shear mechanism composed of a pair of coaxially mounted shear blades which are adapted to be intermittently revolved in opposite directions to move across each other first under the center of one delivery orifice to sever a mold charge from one stream and then to move across each other under the center of the other orifice to sever a charge from the stream issuing through that orifice.

Other attendant objects and purposes of the present invention which presents a number of special features of operation and of structure, will be made apparent to those skilled in this art by the following description of various alternative exemplifications and embodiments of my improved combination of feeder and severing mech-

anism which are illustrated in the accompanying drawings, in which:

Figure 1 is a transverse section elevation on the plane passing through the two orifices of one of my new feeders;

Fig. 2 is a partial longitudinal central section thereof on the plane II—II of Fig. 1;

Fig. 3 is a plan view of feeder construction illustrated in Fig. 1;

Figs. 4 and 5 are respectively vertical section and plan views of a modification of the part of the structure of Figs. 1, 2, and 3;

Fig. 6 is a horizontal section of reduced size through the forehearth illustrated in Fig. 1 on the plane VI—VI of that figure;

Fig. 7 is a partial longitudinal central section on the plane VII—VII of Fig. 1, illustrating the shear operating mechanism;

Fig. 8 is a transverse cross section similar to Fig. 1 through a second form of my dual orifice feeder;

Fig. 9 is a sectional view on line IX—IX of Fig. 8 illustrating the shape of the forehearth;

Fig. 10 is a plan view of the feeder illustrated in Fig. 8 showing the horizontal relationship of the main elements of the assembly; and

Fig. 11 is a side view on reduced scale of the parts of the feeder construction illustrated in Fig. 10.

In general my improved apparatus for forming molten glass into individual mold charges includes a forehearth structure which is attached to the front end of a suitable glass melting tank or furnace and having dual or multiple orifices therein with means associated with each orifice for establishing continuously flowing streams of molten glass therethrough composed of a series of regularly recurrent sections of enlarged diameters connected together by sections of reduced diameters that are adapted to be severed at these points of reduced diameters into individual mold charges. The feeding means are so arranged that an enlarged portion of one stream is being formed while a portion of reduced size is being formed in the other stream, and mechanism is provided for alternately severing these streams into individual preshaped mold charges which are then delivered to a forming machine where the charges are shaped to their finished form. The feeding apparatus, the severing mechanism and the molds of the forming machine are all operated in synchronism with each other and are preferably so timed that a mold charge is delivered to one of the press molds while the charge in the other mold is being pressed into a blank and

30
35
40
45
50
55

the pressed blank is delivered to the blow mold at the same time that another charge is delivered to that mold.

Referring to the drawings in detail, in the embodiment of my invention illustrated in Figs. 1 to 7, inclusive, the feeder comprises an I-shaped forehearth A, having a pair of delivery orifices F—F at the front end, over which a pair of vertically reciprocable bells B—B are positioned that are adapted to be periodically, but alternately, moved up and down to effect the segregation and delivery of preformed mold charges in alternate succession from the two orifices. Each bell B—B is detachably secured to the lower end of a hollow shaft 1, which is rotatably mounted in a ball bearing race 2, that is carried on the outer end of a twin arm radius guide 3, and is partially counterbalanced by an adjustable tension spring 4. The upper portions of the hollow bell shafts 1—1 are encircled by large spur gears 5—5 which are in engagement with each other and which are driven by an elongated pinion 6 that permits the gears to have a considerable range of vertical movement on the shafts 1—1. The pinion 6 carries a bevel gear 7 which is connected through miter gears 8—8 on shaft 9, miter gears 10—10 on cross shaft 11, miter gear 12 on vertical shaft 13 and worm 14 with the drive shaft 15 of a constantly driven variable speed motor 16, consequently the spur gears 5—5 are also continuously driven. These gears 5—5 are not directly connected to the bell shafts 1—1 but are rotatably carried on end thrust ball bearings 17—17 which are supported by pivoted levers 18—18 that are adapted to be rocked up and down on adjustable fulcrum pins 19—19. The levers 18—18 are rocked up and down, to raise and lower the spur gears 5—5, by cams 21—21 on the cross shaft 11, as illustrated at the right of Figs. 2 and 3. A hand operated turnbuckle 22 is connected to each of the bell cranks 20 so that the position of the fulcrum pins 19—19 may be readily varied independently of each other. The cams 21 are so designed and so positioned on the shaft 11 that as one of the pivoted levers 18 is being rocked upwardly to raise the spur gear 5 supported thereby, the other lever 18 is being rocked downwardly to lower the spur gear supported by that lever.

In order to raise and lower the bells B—B as the spur gears 5—5 are being moved up and down through the rocking of the levers 18—18, large disc heads 23—23 are carried on the upper ends of the bell supporting shaft 1—1 which are operatively connected thereto by splined ball and socket joints 24—24. Each of the discs 23 is provided with three adjustable contact screws 25—25—25 that are adapted to engage the adjacent upper surface of the corresponding spur gears 5—5 when the latter is lifted by the action of the lever-cam elements 21, 19, 18, and 17. From this construction, it is apparent that the spur gears 5—5 are lifted alternately into engagement with the corresponding disc head 23 and when this engagement occurs, the head 23 and shaft 1 connected thereto are also raised and are concurrently rotated through the frictional engagement of the screws 25 with the top of the continuously driven spur gear 5; the speed of rotation being determined in part by the viscosity of the glass in which the lower end of the bell is immersed and in part by the amount of unbalanced weight which is supported by the lifted gear wheel 5. The range of upward movement of each bell is regulated and controlled by the adjustment of the fulcrum support 19 for

the lifting lever 18 and the limit of downward movement is fixed by adjustable stop nuts 26—26 on the ends of rods 27—27 which engage the lower side of the radius arm guides 3—3 for the lower ball bearings 2—2 and thus support the bell and 5 shaft assembly in its lowermost position.

The extreme upper ends of each of the hollow bell shafts 1—1 are covered by cups 30—30 having intermediate grooved portions 34'—34'. The upper portions of the cups 30—30 are connected 10 to pressure supply lines 31—31 and the intermediate grooved portions 34'—34' are connected to vacuum conduits 32—32. The closed end of each cup 30 is provided with an adjustable check valve 33 which seats on the end of the hollow bell shaft 1 when the latter is raised to a predetermined height and thus cuts off communication between the pressure supply pipe 31 and the bell or segregation chamber B. The side wall of each of the hollow bell shafts 1—1 is pierced with a 20 row of narrow slots 34 which are so located that when the shaft is moved upward a connection will be established between the vacuum groove 34' in the cup and the chamber in the bell B. Each cup 30 is carried by a U-shaped yoke 35—35 25 which is pivoted at its rear end on the frame of the feeder assembly and is adjustably supported at its front end on a vertical pin 36 so as to vary the time and the degree of opening of the bell chamber to the vacuum connection. The cooperating adjustments of the range of upward movement of the bell shaft 1 through the adjustment of fulcrum pins 19—19, the set position of the pressure check valves 33—33, and the height of the cups 30—30 permits the establishment of the 35 desired relationship between the up and down movement of the bell and the alternate opening and closing of bell chamber B to the pressure and vacuum lines 31—32.

If the mold charges are relatively small in 40 volume, and the depth of the glass in the forehearth is relatively large, the feeder may be operated without the use of the vacuum connection; and in such a case the grooved portion of the bell shaft cap 30 is open to the atmosphere. 45 But if the mold charges are relatively large, or if the bath of glass in the forehearth is relatively shallow it is desirable to use a vacuum (of the proper degree) to expedite the recharging of the 50 segregation chamber at each upward movement of the bell B; and in order to reduce the time of such recharging to a minimum (and thus increase the speed of the operation) I preferably use a low sub-atmospheric pressure (i. e., a high 55 vacuum) and prevent any overcharging action by the provision of a hollow ball float valve 38, made of nichrome, stainless steel, or other suitable material, not injuriously affected by contact with molten glass, which floats upwardly as the 60 level of glass rises in the segregation chamber, and closes communication between that chamber and the hollow shaft 1, thereby preventing the 65 glass from being drawn.

It will be observed that the external force, to 65 which the glass is subjected during the accelerated delivery period—while the glass is being expelled from the delivery orifice under the joint action of gravity and of super-atmospheric pressure—is not released or relieved, that is, the valve 33 does not seat over the upper end of the hollow 70 shaft 1 until the bell has been raised to a substantial height sufficient to establish a free open communication between the interior of the bell B and the surrounding forehearth, and as a result, any retractive action on the outflowing 75

glass—due to the upward movement of the bell—is eliminated. Further, since the slots 34 do not register with the groove 34' in the cup 30, until bell B and shaft 1 have been lifted to substantially the upper limit of their travel, the vacuum (when used) is not applied until the area of the communicating opening between the main body of glass in the forehearth and the interior of the bell is much greater than that of the delivery orifice F; and under such circumstances the flow of glass into the segregation chamber is much more rapid than its outflow through the orifice under the gravity head above it.

The cutting off of each successively formed mold charge at the proper time preferably at the points of natural "necking" is effective by a shear mechanism which is so designed as to operate alternately on the two streams issuing through the dual orifices F—F. This shear mechanism comprises two shear blades 40—41 (Fig. 7), which are mounted on two vertical coaxial shafts 42—43 that are adapted to be intermittently and synchronously rotated in opposite directions. The axis of the shear blade shafts 42—43 is positioned midway between the centers of two delivery orifices F—F and these shafts are periodically and intermittently revolved through 180° to effect the severing operation. One-half revolution causes the oppositely moving shear blades 40—41 to cross each other under the center of one delivery orifice and thus sever the stream flowing therefrom and the succeeding half revolution causes the blades to cut through the center of the stream flowing through the other delivery orifice. At the time of each cut, the shear blades 40—41 are also moved downward at a speed greater than that of the flowing glass so as to prevent any retardation of the flow and also to accelerate the delivery of the severed charge to the receiving mold.

The shear blade supporting shafts 42—43 are journaled in a frame 70 that is pivoted to the bottom of the forehearth structure and the shafts 42—43 are rotated synchronously in opposite directions by a pair of opposed miter gears 44—44, one of which is secured to each of the shafts 42—43 and an intermediate driving pinion 45 on an intermittently driven shaft 69 that is geared through a bevel gear and pinion 67—68 to a vertical shaft 65 having universal joints 66 therein.

In order that shaft 69 will be intermittently driven and the shear blades 40—41 periodically revolved through 180° the lower end of the shaft 66 is secured to a Geneva wheel 63 having three external slots 64 therein. The interval of action of the Geneva wheel 63 is only one-sixth and its interval of rest is five-sixths of the period of revolution of its driving crank 75 which is secured to a vertical shaft 76 that is geared to a central drive shaft 59 by the worm and gear elements 77—78—79—80. The central driving shaft 59 is preferably rotated at a high speed by means of the variable speed motor 16 which is located at one side of the machine and is coupled to a sprocket wheel 81 on the shaft 59 by a silent change drive 82.

In order to impart a downward movement to the shear blades 40—41 as they cross each other under the centers of orifices F—F, to prevent the glass from piling up on the shears and to accelerate the delivery of the severed charge into the receiving mold, the end of the shaft 69 extends through the frame 70 and has a cam 71 secured thereto which engages a roller 72 on the bottom of the forehearth and the downward movement

of the shears is normally resisted by a spring 73 (see right hand end of Fig. 7). In order that the shear blades 40—41 will be driven at the proper speed relative to the forming machine and will be synchronized with the movement of that machine, I prefer to drive the operating mechanism (not shown) of the forming machine from the shaft 59.

The construction illustrated in Figs. 1 to 7 presents a number of novel and useful features which are not of themselves directly involved in carrying out the hereinbefore described mode of operation but which contribute to the effectiveness of the results obtained thereby. Since a considerable part of the forming machine (not shown) is located in close proximity to the feeder forehearth, it is desirable to protect it as completely as possible from radiant heat. In order to accomplish this result I completely enclose the sides and bottom of the forehearth A in a metal box 20 90 that is constructed from sheets of stainless steel or nichrome alloy which have a relatively low coefficient of heat conductivity and which are also highly polished on both their interior and exterior surfaces. I also provide means for preventing the escape of hot gases of combustion through the roof of the forehearth by covering the major portion of it with another metal plate 91 which is provided with raised flanges 92 that form annular pockets 93 around the openings 30 through which the upper ends of the feeder bells B—B and of the baffle gate block 94 project and attaching to the supporting head these members B—B and 94 downwardly extending sheet metal skirts 95 that enter the said pockets 93. These 35 pockets 93 are filled with a suitable fusible metal such as lead, zinc, cadmium alloys that become liquid at the normal temperature of the forehearth roof block and forms a liquid seal between the skirts 95 and the pockets 93. Combustion 40 gases are vented from the forehearth back into the furnace proper and for this purpose, the block 94 is provided with an opening 96 which is located above the glass level. Thus the block 94 performs the function of a skimmer block and a vent. The 45 block 94 may also be lowered to cut off the flow of glass from the furnace to the forehearth and the opening is so located as to be well above the glass level even when the block is in its lowermost position.

It will be apparent to those skilled in the art that various structural changes may also be made in different parts of the previously described combinations without altering its fundamental characteristics of operation. One such exemplary change is shown in Figs. 4 and 5 which illustrate another way of effecting the periodic up and down movement of the feeder bells B—B. In this alternative construction, each of the large spur gears 5'—5' is provided on its under face 60 with a cam surface track a—a that is engaged by two oppositely disposed cam rollers b—b which are mounted on the heads of splined standards c—c. Thus, as the spur gears 5'—5' are rotated, they are periodically moved into engagement with 65 the screws 25 carried by the discs 23—23 and the movement is thus transmitted to the bells B—B. The splined standards c—c may be simultaneously raised or lowered by a pair of worm wheel nuts d—d and worms e—e that are concurrently moved by a suitable handwheel f or other suitable means on the end of a shaft h carrying the worms e—e to vary the maximum lift imparted to the feeder bells B—B by the upward movement of the spur gears 5'—5'. 70

The possibility of substantially varying the mechanical structure of my improved combination without altering its distinctive character is further exemplified by another embodiment of my invention which is illustrated in Figs. 8 to 11, inclusive. In this embodiment, the feeder unit is of the reciprocating bell plunger type—as contrasted with the reciprocated bell-air pressure type of Fig. 1—and comprises two vertically reciprocable bells B' and B' that are positioned over a pair of twin or dual orifices F'—F' in the forehearth A' and the plungers G—G that are vertically reciprocable within the bells B'—B'. Each bell and plunger unit B'—G' and B'—G is adapted to be periodically, but alternately, moved up and down to effect the segregation and delivery of preformed mold charges in alternate succession through the orifices F'—F'.

Each of the bells B'—B' is detachably secured to the lower ends of a sleeve 100 rotatably mounted in a ball race 101 carried by the crosshead 102 and has an external gear 103 thereon which meshes with the corresponding gear 103 on the other sleeve and with an elongated pinion 104 which is secured to a driven shaft 105. Each of the sleeves 100—100 is detachably secured to a collar 106 which is carried on the outer end of a pivoted forked arm 107 that is periodically rocked up and down, to raise and lower the bell B', by a cam 108 on a cam shaft 109 that engages a roller 110 carried on the upper end of a weighted arm 111 that is attached to the inner end of an arm 107 (Fig. 11).

The upper ends of the plungers G—G are detachably secured to hollow shafts 112—112 which extend through open ended cylinders 113—113 carried by the cross-head 114 and each shaft has a piston sleeve 115 mounted thereon which is moved up and down in its respective cylinder 113, to raise and lower the plunger, by suitable motive fluid, such as compressed air, delivered alternately to the opposite ends of the cylinder 113 through pipes 116—117 that are connected to a source of compressed air through a timer valve 118. The timer valves 118—118 are periodically actuated to alternately connect the opposite ends of the cylinder 113—113 to motive fluid by cams 119—119 on the cam shaft 109 which is connected by miter gears 120—120 to a vertical shaft 121a, that, in turn, is geared to the motor shaft 121a, of a continuously driven variable speed motor (not shown). The shaft 105 for rotating the bells B'—B' is also driven from the cam shaft 109 through the gear and shaft elements 122—123—124—125—126.

In order to control and adjust the up and down stroke of the plungers G—G, the open ends of each of the cylinders 113—113 are closed by sleeve nuts 127—127 which are threaded into the ends of the cylinder and are operatively connected to two coaxially mounted rotatable shafts 128 and 129 through the sprocket wheel and chain elements 130—131—132 (upper sleeve nut) and the gear, pinion, sprocket wheel and chain elements 133—134—135—136, and 137, (lower sleeve nut). From this arrangement, it is apparent that each of the sleeve nuts 127—127 closing the ends of each of the cylinders 113—113 is independently movable into and out of their respective cylinders and as a result, the stroke of the pistons 115 and consequently the movement of the plungers G—G may be readily and independently varied and adjusted to control the shape and size of the preformed mold charges.

75 To assist the plungers G—G in expelling the

molten glass segregated in the bells B'—B' through the orifices F'—F' on the down strokes thereof, compressed air is simultaneously introduced into hollow members 140—140 which are formed integrally with the piston sleeves 115—115 and communicate with the interior of the shafts 112—112 and from which it is delivered to the interior of the bells B'—B'. The compressed air is introduced into the members 140—140 through the pipes 141—141 which are connected to a suitable source of such air, at the proper time in the down strokes of the plungers G—G, by cams 142—142 on the cam shaft 109 which actuates a timer valve 143 positioned in the compressed air lines 141—141.

The cams 108—108 controlling the raising and lowering of each of the air bells B'—B' are so arranged on the cam shaft 108 with respect to the cams 119—119 controlling the operation of the plungers G—G that each bell will be moved upwardly before the plunger whereby a flow of glass is established from the forehearth A' through the orifice F' prior to the upward movement of the plunger and as a result, there is no retardation or retraction of the flow through the orifice at the beginning of the up stroke of the plunger, but there is a diminution and a natural necking in the stream as a result of this decelerated flow under the influence of gravity alone. Thus, two continuously flowing streams of glass are produced, each of which is composed of a series of regularly recurrent sections of enlarged diameters connected together by portions of reduced diameters, and since each bell and plunger unit is working alternately with respect to each other, the enlarged portions of one stream are formed, while natural necking is taking place in the other stream, and these streams are adapted to be alternately severed, at the points of reduced diameters, into successive and preformed mold charges that are delivered alternately to the press molds of the forming machine. The mechanism employed for alternately severing the streams of molten glass is the same and is actuated in the same manner as that heretofore described in connection with the construction illustrated in Figs. 1—7, inclusive.

From the foregoing description of my invention it is apparent that each of the feeder mechanisms is readily and independently adjustable, and as a result, uniformity in the mass of the successive mold charges delivered alternately to the press mold tables is readily maintainable. Further, with my improved dual feeder, by rotating the bells concurrently in opposite directions, I am able to produce a symmetrical current circulation in the forehearth which may be flowing in the same direction or in the opposite direction to the currents of heating gases introduced into the forehearth through the burners 200—200 (Fig. 6) and consequently the molten glass in the forehearth is maintained at a more nearly uniform temperature than can be secured with the present feeding mechanism since this concurrent rotation of the dual feeding devices in opposite directions keeps the molten glass well agitated and prevents the localization of cold spots therein.

What I claim as new and desire to secure by Letters Patent is:

1. An apparatus for delivering individual mold charges of molten glass comprising a forehearth having twin orifices in the bottom thereof, means for periodically segregating a quantity of material over each of said orifices, means for periodically expelling the segregated masses through

70

75

80

85

90

95

5 said orifices, and common means for alternately severing the glass issuing through said orifices into individual mold charges, including a pair of oppositely rotating shear blades adapted to cross each other at every half revolution first under one and then the other of said orifices.

2. An apparatus for delivering individual charges of molten glass comprising a container for molten glass having two submerged orifices 10 therein, means for segregating a quantity of glass over one of said orifices, means for expelling the segregated quantity through said orifice, means operable during the expelling of such segregated quantity for segregating a quantity of material 15 over the other of said orifices, means for expelling the last-mentioned quantity through the orifice, and common means for alternately severing the glass flowing through each of said orifices into individual mold charges.

20 3. A feeder for molten glass comprising a container having dual submerged orifices therein through which the glass issues, a vertically reciprocable hollow member positioned over each of said orifices, means for alternately raising and 25 lowering each of said members, means associated with said members for applying an extruding force to the material over said orifices when said members are moved to their lowermost positions, and a pair of oppositely rotating shear blades having 30 adapted to cross each other first under one of said orifices and then under the other to sever the streams issuing therethrough, said shear blades being so correlated to said member raising and lowering means that they cross each other 35 under each of said orifices as the hollow members positioned thereover are moving therefrom.

4. In combination in a glass feeder, a forehearth having two spaced submerged orifices formed in the floor thereof, bells extending downwardly through the mass of molten glass in said 40 container, one in axial alignment with each orifice for controlling the flow through such orifices, and means for periodically rotating said bells in opposite directions to create a definite circulation 45 within such mass.

5. An apparatus for delivering mold charges of molten glass comprising a forehearth having a pair of spaced flow orifices in the bottom thereof, an air bell mounted above and in vertical alignment with each of said orifices, a rotating spur 50 gear loosely mounted on each of said bells, means for alternately raising and lowering said rotating spur gears, means on said bells adapted to be engaged on the upward movement of said rotating gears for raising and rotating said bells, means operable as said bells are raised for connecting the interior to a source of vacuum, means operable as said bells are lowered for introducing fluid pressure into said bells, and a single means for 55 alternately severing the streams issuing through said orifices.

6. In combination with a container for molten glass having a plurality of submerged orifices therein through which the glass issues, a mechanism for successively severing the streams issuing through said orifices comprising a pair of coaxially mounted shear blades, means for rotating said blades in opposite directions to cause them to successively cross each other under the center of each said orifice, and means for moving 65 said blades in the direction of travel of said stream as the blades cross each other in cutting engagement.

7. In combination with a container for molten glass having a pair of submerged orifices therein 70

through which the glass issues in streams, mechanism for successively severing the streams of glass flowing through said orifices into individual mold charges comprising a pair of coaxially mounted shear blades, means for intermittently 5 rotating said blades in opposite directions and through a half revolution to move said blades across each other first under the center of one orifice and then under the center of the other orifice, and means associated with said blades 10 for imparting a transverse movement thereto as they cross each other under said orifices.

8. In combination with a container for molten glass having two submerged discharge orifices therein through which the glass issues in continuous streams, a mechanism for successively severing the streams of glass flowing through said orifices into individual mold charges comprising a pair of coaxially mounted shear blades having their common axis located intermediate said orifices, a common shaft for rotating said blades in opposite directions, means for intermittently driving said shaft to turn said blades through one-half a revolution whereby the blades cross each other successively under said orifices, and sever 15 said streams, and means carried by said shaft for moving said blades in the direction of flow of said streams as they cross each other under each orifice.

20 9. In combination with a container for molten glass having a pair of spaced submerged discharge orifices therein, through which the glass issues in continuous streams, a mechanism for successively severing the streams of glass flowing through said orifices into individual mold 25 charges comprising a pair of coaxially mounted shear blades having their common axis positioned midway between said orifices, a common shaft for rotating said blades in opposite directions, a Geneva wheel operatively connected to 30 said shaft, means for driving said Geneva wheel to intermittently turn said shaft and rotate said blades through one-half of a revolution at a time whereby said blades cross each other first under one and then under the other of said orifices, and means carried by said shaft for moving 35 said blades in the direction of flow of said streams as they cross each other under said orifices.

40 10. A glass feeder comprising a container for molten glass having a plurality of submerged discharge outlet openings therein, a plurality of vertically movable air bells extending into the glass within said container one of which is in axial alignment with each of said outlets, a 50 member associated with each of said bells and rotating relative thereto, separate means for reciprocating each of said rotating members, and means carried by each bell adapted to be frictionally engaged by its respective rotating member on the upward movement thereof to raise 55 and rotate each of said bells.

11. A glass feeder comprising a container for molten glass having a plurality of submerged discharge orifices therein, a plurality of vertically movable air bells extending into the glass within said container one of which is in axial alignment with each of said orifices, a member carried by each of said bells and movable relative thereto, means for rotating said members, 65 separate means for reciprocating each of said members and a member carried by each bell adapted to be frictionally engaged by said rotating member on the upward movement thereof to raise and rotate said bell, the means for 70

- reciprocating said rotating members being so timed that one bell is moved upwardly and rotated while another is moving downwardly through said glass.
5. 12. A glass feeder comprising a container for molten glass having a plurality of submerged discharge outlet openings therein, a plurality of vertically movable air bells extending into the glass within said container one of which is in axial alignment with each of said outlets, a tube connected to each of said air bells, a rotating member slidably mounted on each of said tubes, a vertically adjustable member secured to each of said tubes above said slidably mounted and rotating member, and separate means for periodically moving each of said rotating members into engagement with the members secured to said tubes whereby each of said bells is periodically raised and rotated.
10. 13. A glass feeder comprising a container for molten glass having a pair of spaced outlet openings therein, a vertically movable bell axially aligned with each outlet, means for alternately connecting the interior of said bells to sources of pressure and vacuum, and separate means for alternately reciprocating and rotating each of said bells, said last-mentioned means including a rotating member movable relative to each of said bells, a second member adjustably secured to each of said bells above said rotating members, and means for periodically moving each of said rotating members into frictional contact with said second-named members to thereby raise and rotate said bells.
15. 14. A glass feeder comprising a container for molten glass having a pair of spaced outlet openings therein through which the glass issues, a vertically movable air bell axially aligned with each outlet, means for alternately connecting the interiors of said bells to sources of pressure and vacuum, and separate means for alternately reciprocating and rotating each of said bells, each of said last-mentioned means including a rotating member movable relative to said bell, a second member adjustably secured to said bell above said rotating member, and means for periodically raising said rotating member to move it into frictional contact with said second-named member to thereby raise and rotate said bell, the means for reciprocating said rotating members being so timed that one bell is raised and rotated while another is moving downwardly.
20. 15. A glass feeder comprising a container for molten glass having a pair of spaced outlet openings therein through which the glass issues, a vertically movable air bell axially aligned with each outlet, means for alternately connecting the interior of each said bell to sources of pressure and vacuum, separate means for alternately reciprocating and rotating each of said bells, each of said last-mentioned means including a rotatable member movable relative to said bell, means for rotating said member, a second member adjustably secured to each of said bells above said rotating member, and means for periodically raising said rotating member to move it into frictional contact with said last-mentioned member to thereby raise and rotate said bell, and a single means for alternately severing a mold charge from the streams issuing through said orifices.
25. 16. A glass feeder comprising a container for molten glass having a plurality of outlet openings therein, a plurality of reciprocable sleeves extending into said container one of which is in axial alignment with each of said outlets, means for rotating each of said sleeves, separate means for reciprocating each of said sleeves, a plunger extending into each sleeve and separate means for reciprocating each of said plungers, the sleeve reciprocating means being so timed that one sleeve is moving upwardly while another is moving downwardly.
30. 17. A glass feeder comprising a container for molten glass having a plurality of outlet openings therein, a plurality of reciprocable sleeves extending into said container one of which is in axial alignment with each of said outlets, separate means for reciprocating each of said sleeves, said means being so timed that one sleeve moves away from its outlet while another moves toward its outlet, means for rotating said sleeves and vertically movable plungers for forcing the material in said sleeves through said outlets one of said plungers being mounted in each of said sleeves, said plungers being adapted to reciprocate in timed relation with the reciprocation of its respective sleeve.
35. 18. A glass feeder comprising a container for molten glass having a plurality of outlet openings therein, a plurality of vertically reciprocable sleeves extending into the glass in said container one of which is in axial alignment with each outlet, separate means for reciprocating each of said sleeves, said means being so timed that one sleeve moves away from its outlet while another moves toward its outlet, means for rotating said sleeves, a plunger extending into each of said sleeves, separate means for reciprocating each of said plungers to discharge the glass in its respective sleeve through the outlet on the downstroke thereof, and means for periodically connecting the interior of each sleeve to a source of fluid pressure to assist its plunger in discharging the glass through the outlet.
40. 19. A glass feeder comprising a container for molten glass having a plurality of outlet openings therein, a plurality of reciprocable sleeves extending into the glass within said container one of which is in axial alignment with each outlet, separate means for reciprocating each of said sleeves, said means being correlated so that one sleeve moves away from its outlet while another moves toward its outlet, means for continuously rotating said sleeves, a reciprocating plunger extending into each of said sleeves, a piston connected to reciprocate with each of said plungers, a cylinder in which each piston reciprocates, and means for delivering fluid pressure to alternate ends of said cylinder.
45. 20. A glass feeder comprising a container for molten glass having a plurality of outlet openings therein, a plurality of reciprocable sleeves extending into the glass within the container one of which is in axial alignment with each outlet, separate means for reciprocating said sleeves, said means being so timed that one sleeve moves away from its outlet while another moves toward its outlet, means for continuously rotating said sleeves, and means for discharging the glass in said sleeves through said outlets, each of said last-mentioned means including a reciprocating plunger extending into each of said sleeves, a piston connected to reciprocate with said plunger, a cylinder in which said piston reciprocates, means for delivering fluid pressure to alternate ends of said cylinder, and means for varying the movement of said piston within said cylinder.
50. 21. A glass feeder comprising a container for

molten glass having a plurality of outlet openings therein, a plurality of reciprocable sleeves extending into said container one of which is in axial alignment with each of said outlets, separate means for reciprocating each of said sleeves, a plunger extending into each of said sleeves and separate means for reciprocating each of said plungers, the sleeve reciprocating means being so timed that one sleeve is moving upwardly while another is moving downwardly.

22. A glass feeder comprising a container for molten glass having a plurality of outlet openings therein, a plurality of reciprocable sleeves extending into said container, one of which is in axial alignment with each of said outlets, separate means for reciprocating each of said sleeves, said means being so timed that one sleeve is moving away from its outlet while another sleeve is moving toward an outlet, and vertically movable plungers for expelling the material within said sleeves through said outlets, one of said plungers being mounted in each of said sleeves, said plungers being adapted to reciprocate in timed relation with the reciprocation of its respective sleeve.

23. Apparatus for delivering individual mold charges of molten glass comprising a container for molten glass having two submerged discharge outlets therein, through which glass issues in continuously flowing streams, means for alternately accumulating a quota of glass over each said outlet, means for expelling the accumulated quota through one outlet while the quota is being accumulated over the other outlet, and common means for alternately severing the glass flowing through each said outlet into individual mold charges.

24. Apparatus for delivering individual mold charges of molten glass comprising a container for molten glass having two submerged discharge outlets therein, through which glass issues in continuously flowing streams, means for alternately accelerating the flow through each said outlet, and common means for alternately severing the streams flowing through each outlet into individual mold charges.

25. Apparatus for delivering individual mold charges of molten glass comprising a container

for molten glass having two submerged discharge outlets therein through which glass issues in continuously flowing streams, a single shear mechanism for alternately severing the streams flowing through said outlet into individual mold charges, and means associated with said shear mechanism for moving said shear in the direction of flow of said stream during the severing operation.

26. Apparatus for forming and delivering individual mold charges of molten glass comprising a container for molten glass having a plurality of submerged discharge outlets therein, a plurality of reciprocable sleeves extending into said container one of which is in axial alignment with each of said outlets, means for reciprocating each of said sleeves, means for alternately connecting each of said sleeves to sources of pressure and vacuum to vary the flow through said outlets, and common means for severing the glass flowing through each of said outlets into individual mold charges.

27. Apparatus for forming and delivering individual mold charges of molten glass comprising a container for molten glass having a plurality of submerged discharge outlets therein, a plurality of reciprocable sleeves projecting into said container formed in axial alignment with each of said outlets, means for periodically expelling glass within each said sleeve through its respective outlet, and common means for severing the glass flowing through each said outlet into individual mold charges.

28. Apparatus for forming and delivering individual mold charges of molten glass comprising a container for molten glass having a plurality of submerged discharge outlets therein through which the glass issues in a continuously flowing stream, a plurality of reciprocable sleeves extending into said container one in axial alignment with each of said outlets, means for reciprocating each of said sleeves in timed relation with each other, means for expelling the glass within each said sleeves through its respective outlet to accelerate the flow therethrough, common means for successively severing the glass flowing through each said outlet, and means for accelerating the delivery of such severed charges.
